ELECTRONIC AUDIO SWITCH

William D. Houghton, Port Jefferson, N. Y., assignor to Radio Corporation of America, a corporation of Delaware

Application June 30, 1945, Serial No. 602,447

9 Claims. (Cl. 250—27)

1

This invention relates to an electronic switching circuit, and particularly to a method of and apparatus for electronically controlling the audio output of a system by means of a direct current or low frequency alternating current voltage.

The invention may be used in signalling systems employing speech or other audio modulation and wherein it is desired to reduce the effects of the speech or audio modulation from a part of the system when a calling or ringing voltage is applied. In such systems, the calling or ringing voltage may be a low frequency alternating current (for example, 20 cycles per second) which is utilized to actuate an alarm and thus attract the attention of the operator at the receiving end of the system.

Briefly, the invention comprises a vacuum tube which is normally biased to the anode current cut-off condition, and to which both the audio modulation and the ringing voltage are applied. The application of the ringing voltage causes the vacuum tube to conduct and produce an effective short-circuit (low impedance path) across a resistor across which the audio modulation is applied through a condenser. This low impedance path reduces the effective amplitude of the modulation waves across the resistor to a low value.

A feature of the invention lies in the circuit scheme which converts the low frequency ringing voltage to a direct current voltage which is used, in one application of the invention to a pulse signalling system, to advance the time at which a pulse is transmitted and at the same time reduces the amplitude of the audio voltage applied to the system.

A more detailed description of the invention follows, accompanied by drawings, wherein the same parts throughout the figures are represented by the same reference characters.

In the drawings:

Fig. 1 is a circuit diagram given to illustrate the principles of the present invention;

Fig. 2 illustrates a general application of the present invention; and

Fig. 3 illustrates the invention as applied to a pulse generator modulator circuit.

Fig. 1 illustrates the basic circuit of the invention and is given for the purpose of clearly setting forth the principles involved. This figure illustrates a triode vacuum tube V1 having an anode A to which a positive potential is supplied from a unidirectional current source +B, a grid G, and a cathode K. In the cathode circuit there is provided a rather high value of resistor R1 connected between the cathode and ground. Connected between the grid and ground there is provided a resistor R2 in series with a battery E, which is so poled as to supply a negative potential to the grid to thereby bias the vacuum tube V1 normally below cut-off. A switch S is shown

2

connected between the grid and ground so as to shunt or short-circuit resistor R2 and battery E when the switch is in closed position. A suitable source of audio frequency input waves, for example speech modulation waves, is shown connected to terminals 1 and 2. Terminal 2 is connected to ground while terminal 1 is connected through condenser C1 to the cathode K of the tube. The output terminals are labeled 3 and 4 and these are connected respectively to the cathode K and to ground. Resistor R1 has a value sufficiently high so that the audio response in output terminals 3 and 4 is satisfactory.

When switch S is closed, the negative bias on the grid G is removed and the normally cut-off or non-conductive tube V1 will conduct, as a result of which the impedance across resistor R1 becomes low for the alternating current input waves developed across resistor R1 and emanating from terminals 1 and 2. When tube V1 conducts, most of the alternating current audio input voltage is caused to be developed across condenser C1, resulting in a reduction in the amplitude of the audio output voltage appearing on output terminals 3 and 4.

In effect, when tube V1 conducts, the effective impedance across resistor R1 is reduced from the relatively high value of the resistor R1 to a much lower value. Condenser C1 has normally a low impedance compared to R1 for audio voltages but its impedance is rather high compared to the impedance shunted across resistor R1 for these same audio voltages during the time tube V1 conducts, as a result of which most of the audio voltage is developed across the condenser C1 when tube V1 is conducting. The low impedance across resistor R1 acts as an effective short circuit or low impedance path to ground for the audio voltage developed across condenser C1 and prevents its effective application to output terminal 3.

The effective impedance shunted across resistor R1 when the tube conducts is given by the formula

$$Z = \frac{R1}{1 + R1Gm}$$

where Gm is the transconductance of the vacuum tube. If R1 is, for example, 1 megohm, and the Gm of the vacuum tube used is 2000 micromhos, the impedance offered by tube V1 to the audio input waves is approximately 500 ohms with the switch S closed. Hence, when resistor R1 appears as 500 ohms, most of the voltage drop will be across condenser C1.

Fig. 2 illustrates one embodiment of the invention wherein a low frequency ringing voltage (for example 20 cycles per second) is rectified and the resultant D. C. applied to the grid of tube V1 for effectively causing a reduction in amplitude of the output voltage. The circuit of Fig. 2 is essen-

entially the same as that of Fig. 1, with the exception that the triode tube V_1 is normally biased below the anode current cut-off condition and is caused to conduct by rectifying the audio ringing voltage applied to terminals 5 and 6. The ringing voltage applied to terminals 5 and 6 is passed through condensers C_3 and C_4 to a diode rectifier V_2 having in circuit therewith a suitable filter network C_2 , R_2 . This ringing voltage is rectified by diode V_2 , causing a D. C. voltage to be developed across resistor R_3 of such nature that a voltage of positive polarity is coupled to grid G via resistor R_2 . The constants of the filter C_2 , R_2 are such that the D. C. voltage developed across condenser C_2 and applied to grid G is constant for the duration of the applied ringing. This positive voltage on the grid G is of sufficient value to overcome the cut-off bias on the tube V_1 and cause the tube V_1 to conduct, thereby causing voltage to be developed across resistor R_1 which is positive with respect to ground at the cathode K . The result of tube V_1 conducting is to reduce the effective impedance across resistor R_1 and consequently reduce the audio modulation fed to output terminals 3 and 4 while at the same time producing a positive voltage relative to ground at terminal 3. This last positive voltage is approximately equal to the positive voltage applied to the grid G . The low impedance across resistor R_1 acts as an effective short circuit for the audio voltage developed across this resistor, via C_1 .

In one embodiment of the invention in Fig. 2 the tube V_1 was an RCA 6SL7 type tube, the resistor R_1 had a value of one-half megohm, the condenser C_1 had a value of $.01\mu f$, the condenser C_2 had a value of $.1\mu f$, the resistor R_2 was 270,000 ohms, the resistor R_3 was 270,000 ohms and resistor R_4 was 270,000 ohms.

Fig. 3 illustrates how the electronic audio switch can be applied to a phase modulator and pulse generator shown to the left of the vertical dash line. Such a phase modulator and pulse generator is described by way of example in my copending application Serial No. 617,634 filed September 20, 1945, describing a pulse signaling system. The electronic audio switch of the invention comprising vacuum tube V_1 and its associated circuit elements, operates in a manner described above in connection with Fig. 2.

The phase modulator and pulse generator comprises a triode vacuum tube V_3 to which is applied (via terminal 7) periodically recurring saw-tooth voltage waves. Tube V_3 is normally biased to cut-off and has its cathode connected to the anode of a modulator tube V_4 . Tube V_4 acts as a variable resistor.

In effect, tube V_3 is a pulse generator which is so biased as to start to conduct at about the middle of the applied saw-tooth voltage wave in the absence of audio modulation input from terminals 1, 2. The modulation on terminals 1 and 2 is applied to tube V_3 by means of tube V_4 which serves to vary the bias on tube V_3 and hence to vary the critical value or time at which tube V_3 starts to conduct over the slope of the saw-tooth wave impressed on the terminal 7. Transformer T_1 is a differentiating transformer which provides a pulse output at terminal 8 of sharp rise and decay when a rapid current change occurs in tube V_3 . The normal bias on tube V_4 is set by the tap on its cathode resistor R_5 , and hence the variation in grid voltage of tube V_4 changes the applied anode resistance of this tube and hence the cathode bias of tube V_3 . Any appreciable flow of current through tube V_3 must be through tube

V_4 and R_2 has a very high value of resistance. The maximum advanced position in time of tube V_3 due to modulating voltage is determined by the minimum anode resistance of tube V_4 (maximum conduction position) which occurs when positive voltage is applied to the grid of tube V_4 . When ringing is applied to terminals 5 and 6, the tube V_1 will conduct and apply a positive D. C. voltage on the grid of tube V_4 for the duration of the ringing. This positive voltage on the grid of tube V_4 will cause this tube to assume its maximum conduction position, thus advancing the conducting time of pulse generator tube V_3 relative to the saw-tooth voltage wave, as a result of which the pulse at terminal 8 in the output of the generator is advanced in time compared to the position which this output pulse would normally occupy when tube V_1 is cut off. During this applied ringing, the audio applied at terminals 1 and 2 is reduced due to the previously described action of tube V_1 .

The invention is not limited to the use of a condenser C_1 , since this particular circuit element can be any impedance, such as a capacitor (as shown), an inductor or a resistor, and the operation would be substantially the same. By way of example, let it be assumed that C_1 is a resistor equal in value to R_1 , i. e. 100,000 ohms and that tube V_1 has a G_m of 200 micromhos. Then when tube V_1 is cut off, the voltage at terminals 3 and 4 would be one-half or 6 db. less than the voltage at terminals 1 and 2. When tube V_1 is conducting, the shunted impedance is approximately ohms as obtained from the formula

$$Z = \frac{R_1}{1 + R_1 G_m}$$

The voltage at 3 and 4 in this case is .005 times the voltage at the input or 46 db. less than the level at 1 and 2. Hence a reduction of 40 db. can be obtained.

The term "ground" used in the appended claims is deemed to include any point or surface of zero potential for D. C. or alternating current.

What is claimed is:

1. An electronic switch comprising a vacuum tube having an anode, a cathode and a control electrode, a source of unidirectional potential supplying positive potential to said anode relative to the cathode, a resistor connecting said cathode to ground, means normally biasing said tube to the anode current cut-off condition, said means including a resistor in series with a source of unidirectional potential connected between said control electrode and ground, an output terminal for said system comprising a connection to said cathode, a condenser having one side connected to said cathode, the other side of said condenser being adapted to be connected to a source of audio voltage, a rectifier in circuit with said grid for rectifying an alternating current voltage adapted to control said switch, to thereby supply said grid with a positive potential of sufficient magnitude to overcome said bias and cause said tube to conduct, and a filter coupled to said grid and rectifier and having such constants as to assure a substantially constant rectified voltage for said grid for the duration of the applied alternating current control voltage.

2. An electronic switch comprising a vacuum tube normally biased beyond cut-off, said tube including a cathode and a grid, an output lead connected to said cathode, a pair of connections for supplying an alternating current voltage

whose effective value in said output lead is to be controlled, a relatively high value resistor connecting one of said connections to said cathode, a condenser connecting the other of said connections to said cathode, and means for controlling said tube to reduce the output thereof in accordance with another alternating current voltage, said means including a rectifier in circuit with said grid for rectifying said last alternating current voltage and for supplying said grid with rectified voltage of positive polarity and sufficient magnitude to overcome said bias and cause said tube to conduct.

3. An electronic switch comprising a vacuum tube normally biased beyond cut-off, said tube including a cathode and a grid, an output lead connected to said cathode, a pair of connections for supplying an alternating current voltage whose effective value in said output lead is to be controlled, a relatively high value resistor connecting one of said connections to said cathode, a condenser connecting the other of said connections to said cathode, and means for controlling said tube to reduce the output thereof in accordance with another alternating current voltage, said means including a rectifier in circuit with said grid for rectifying said last alternating current voltage and for supplying said grid with rectified voltage of positive polarity and sufficient magnitude to overcome said bias and cause said tube to conduct.

4. An electronic switch comprising a vacuum tube normally biased beyond cut-off, said tube including an anode, a cathode and a grid, means for supplying said anode with positive polarizing potential relative to the cathode, an output lead connected to said cathode, a pair of connections for supplying an alternating current voltage whose effective value in said output lead is to be controlled, a resistor of a relatively high value connected at one end to said cathode, the other end of said resistor being connected to one connection, the other of said connections including a serially arranged condenser also connected to said cathode, the impedance of the condenser being low compared to the impedance of said resistor for said alternating current voltage, and means for supplying said grid with a positive potential of sufficient magnitude to overcome said bias and cause said tube to conduct, to thereby reduce the alternating current output voltage in said output lead.

5. An electronic switch comprising a vacuum tube normally biased for a predetermined limiting conduction condition, said tube including an anode, a cathode and a grid, means for supplying said anode with positive polarizing potential relative to the cathode, an output lead connected to said cathode, a pair of connections for supplying an alternating current voltage whose effective value in said output lead is to be controlled, a resistor of a relatively high value connected at one end to said cathode, the other end of said resistor being connected to one of said connections, the other of said connections including a serially arranged condenser also connected to said cathode, and means for supplying said grid with a potential of such polarity and magnitude as to overcome said bias and change the condition of said tube from said predetermined limiting conduction condition to another conduction condition.

6. An electronic switch in accordance with claim 4, including a rectifier and a filter circuit coupled to said grid for enabling the control of said tube from another alternating current voltage.

7. An electronic switch comprising a vacuum tube normally biased beyond cut-off, said tube including an anode, a cathode and a grid, means for supplying said anode with positive polarizing potential relative to the cathode, an output lead connected to said cathode, a pair of connections for supplying an alternating current voltage whose effective value in said output lead is to be controlled, a resistor of a relatively high value connected at one end to said cathode, the other end of said resistor being connected to one connection, the other of said connections including a serially arranged impedance element also connected to said cathode, the impedance of the impedance element being low compared to the impedance of said resistor for said alternating current voltage, and means for supplying said grid with a positive potential of sufficient magnitude to overcome said bias and cause said tube to conduct, to thereby reduce the alternating current output voltage in said output lead.

8. An electronic switch comprising a vacuum tube normally biased beyond cut-off, said tube including a cathode and a grid, an output lead connected to said cathode, a pair of connections for supplying an alternating current voltage whose effective value in said output lead is to be controlled, a relatively high value resistor connecting one of said connections to said cathode, an impedance element connecting the other of said connections to said cathode, and means for controlling said tube to reduce the output thereof in accordance with another alternating current voltage, said means including a rectifier in circuit with said grid for rectifying said last alternating current voltage and for supplying said grid with rectified voltage of positive polarity and sufficient magnitude to overcome said bias and cause said tube to conduct.

9. An electronic switch comprising a vacuum tube normally biased beyond cut-off, said tube including a cathode and a grid, an output lead connected to said cathode, a pair of connections for supplying an audio voltage whose effective value in said output lead is to be controlled, a resistor connecting one of said connections to said cathode, an impedance element connecting the other of said connections to said cathode, and means for controlling said tube to reduce the output thereof in accordance with an alternating current voltage, said means including a rectifier in circuit with said grid for rectifying said last alternating current voltage and for supplying said grid with rectified voltage of positive polarity and sufficient magnitude to overcome said bias and cause said tube to conduct.
